Application September 26, 1950, Serial No. 186,808

5 Claims. (Cl. 202—6)

Our invention relates to improved means for effecting the coking of hydrocarbon oils in the presence of a body of coke particles maintained in circulation within a reaction vessel at a coking temperature. A basic difficulty in treating the residual oils for maximum recovery of distillate oil by coking is in the handling of the coke product. Conventionally, coking processes usually operate on a semi-continuous basis by charging oil to a coking chamber until the chamber is filled with coke and then switching to another coking chamber while discharging the coke from the first chamber. Because of the cost and difficulty involved in cooling and discharging the coke agglomerate from the usual coking chamber, coking processes have had limited commercial acceptance for preparation of cracking charge stocks from residual oils and for the reduction of residual oils to a minimum quantity of non-distillable product. In application Serial No. 121,575 filed October 15, 1949, Kenneth M. Watson has described a continuous coking system wherein the residual oil is introduced to a body of coke particles which is maintained in a fluidized condition in a reaction vessel from which large particles are continuously and selectively withdrawn as formed to maintain the reaction system in equilibrium. In this way, the coke is selectively deposited on the adsorbent surfaces of the coke particles without troublesome deposit on the metal surfaces of the equipment and gradual build-up as an agglomerate filling the reaction vessel.

Successful operation of the Watson process requires that the coke particles be maintained in agitation or circulatory motion to prevent solidification of the bed halting the process, to effect uniform distribution of the oil charge within the reaction zone in order to promote the coking reaction to the optimum extent and to permit withdrawal of the coke product in the form of large coke particles by elutriation. Because of the difficulty in vaporizing the charge oil and because of the mass of coke particles required in the reaction vessel to provide the substantial time factor needed for the coking reaction, large quantities of steam or other vaporous media are required to maintain the body of coke particles in circulatory motion in reasonably uniform contact with the oil charge. Although steam requirements are reduced for the same volume of coke particles by increasing the ratio of bed height or length to diameter (L/D), increase in the ratio of the height to the diameter is limited by the occurrence of slugging or bumping resulting in loss of contact between coke particles and vapors, excessive coke carry-over with the reactor vapor effluent and possible damage to the equipment. We have now devised, however, a system for effecting circulation of coke particles within the reaction vessel which improves contact of the adsorbent coke particles with the oil charge, permits the use of high L/D beds and appreciably reduces the requirements for steam or other vaporous media. Our invention also is particularly adapted to economically developing and maintaining very high coking temperatures within the reaction zone.

According to our invention, a body of coke particles is maintained in a vertically enlarged reaction vessel into a lower portion of which the hydrocarbon oil charging stock is continuously introduced. A stream of coke particles is circulated upwardly in the body of coke particles through an internal passageway of restricted cross-sectional area, or chimney. Circulation is maintained by injection of high velocity steam or other vapor at a

2

low point in the body of coke particles and continues from above the internal passageway downward through the annulus around the passageway. The downwardly circulating particles are deflected inwardly toward the internal passageway and through a restricted annular outlet section to the region of the body of coke particles below the internal passageway. The preheated hydrocarbon charge oil is injected into the body of coke particles below the internal passageway, large coke particles are selectively withdrawn from a lower portion of the reaction vessel by elutriation, and vapors are withdrawn overhead from an upper portion of the reaction vessel.

Two coking reactors of our invention are illustrated diagrammatically and in section in the accompanying drawings. From a consideration of the drawings, it will be apparent that the coking reactors of our invention are characterized structurally by a tapered or funnel-like shape to the lower section of the reaction vessel in cooperating relation with a cylindrical open-ended reactor internal or chimney vertically disposed within the reaction vessel.

In the attached drawings Figure I is a diagrammatic view of one form of the invention showing the reactor vessel including the internal passageway having a funnel-shaped section below the internal passageway; Figure II is a diagrammatic view of a second form of the invention showing the enlarged annular section surrounding the lower portion of the chimney and means for introducing combustion air to this enlarged section.

In the coking reactor of Figure I, preheated black oil charge is introduced into reaction vessel 10 through line 11 and dispersion nozzle 12. Dispersion steam may be provided through connection 13 if desired. A body of coke particles with the approximate bed level indicated at 14 is maintained within the reaction vessel 10. Disposed within the reaction vessel 10 is an open-ended internal cylinder or chimney 17 providing an internal passageway upwards through the body of coke particles within reaction vessel 10. The lower portion of the reaction vessel 10 is a tapered or funnel-shaped section 15 which opens into elutriator pipe 16. The point of oil introduction is into the body of coke particles below the lower open end of internal passageway 17 in such a manner as to obtain good dispersion and contribute to the circulation of the coke particles upward through the internal passageway. Circulation is effected by injection of steam or other vapor through connection 30. The point of vapor injection is at the low point in the bed in order to avoid stagnant areas below the point of inlet. Elutriating steam is injected at a lower portion of elutriator 16 by means of connection 18, and the larger coke particles built up in the process settle from the system through the annular section surrounding the circulation vapor inlet against the rising elutriation vapors. Under the influence of the circulation steam, the elutriator steam and the dispersed charge oil, circulation of coke particles and adsorbed oil is effected upward through the internal chimney 17 and downward through the surrounding annulus 17A. The inward deflection of the descending particles accelerated by passage through the relatively restricted annular outlet section 17B appears to have a surprising influence on maintenance of the desired circulation. Large coke particles formed by build-up of coke from the charge oil are selectively withdrawn through elutriator pipe 16, at a rate controlled by steam injection through connection 18. Lock hopper 19 is provided to control flow of coke product from elutriator 16 and to maintain or remove the body of coke particles from the reaction vessel 10. Oil and steam vapors are removed overhead from the reaction vessel 10 through line 20 to a distillate oil recovery system.

In the coking reactor illustrated in Figure II, preheated oil charge is introduced to the reaction vessel 50 by line 51 and dispersion nozzle 52. Dispersion steam may be introduced if desired through connection 53. A body of coke particles having an approximate bed level at 54 is maintained within the reaction vessel 50. Opening into the tapered bottom of the reaction vessel 50 is elutriator 56 into which elutriating steam is admitted through connection 57 and in which lock hopper 58 is provided to control flow of coke product from elutriator 56 and to

3

maintain or remove the body of coke particles from the reaction vessel 50. Circulation steam is introduced through line 71 to maintain circulation while coke particles descending down the walls of the tapered section of the reaction vessel 50 contact the elutriation vapors in the annular section surrounding line 71. Disposed within the reaction vessel 50 is an open-ended cylinder or chimney 59 providing an internal passageway up through the bed having its lower end situated above the point of oil injection. In the lower region of the reaction vessel an enlarged section 60 is provided surrounding the lower section of the internal chimney 59. In this especially advantageous form of our invention, the enlarged section 60 is provided so that air may be introduced in its lower region through connection 63, bustle pipe 64 and discharge orifices 65. The purpose of the air injection is to provide controlled burning of a portion of the coke made in the reaction in order to obtain a particularly high coking temperature for the reaction. Preferably, the enlarged annular section 60 is equipped for gas firing to insure proper ignition as by injection of fuel gas through line 72, bustle pipe 73 and jets 74. With continuous gas firing, excess air is supplied so that some coke is burned. Flue gas is removed from the upper portion of the enlarged annular section 60 through hooded disengaging pipes 66; collector section pipe 66A and line 67. Sealing steam is introduced through connection 68 and bustle pipe 69 above the point of flue gas exit in order to avoid combustion of oil vapors or oil adsorbed on the surfaces of the coke particles in the upper portion of the coke bed which is not yet reduced to coke, and to prevent the flue gas from contaminating the oil vapors and loading gas plant. Oil and steam vapors are removed overhead from reaction vessel 50 through line 70 and the distillate oil product is separated in the usual product recovery system.

In operation according to our invention, a circulating motion within the body of coke particles is maintained and supplemented by injection of steam to the lower portion of the body of coke particles by action of the steam injected through the elutriator and to some extent by action of the vaporized and dispersed charge oil. The stream of coke particles moves upwardly through the internal passageway disposed within the reaction vessel to the upper level of the bed as a dilute phase; i. e. as low as 2-3 pounds per cubic foot in density. Coke particles descend from the upper portion of the bed downward through the annular passageway by gravity but are aided to an important extent by means of the accelerating effect of the deflection of the descending stream of particles through the relatively restricted lower annular outlet section or orifice inwardly to join the ascending stream of coke particles. Thus, the bed appears to descend at a uniform velocity through the annulus until it reaches the tapered section where the descending body of particles is turned in and tends to be swept up by the steam injected at the foot of the bed. A level of coke above the top of the chimney is advantageous in that it tends to baffle the flow from the top of the chimney. The bed level should not be so high as to form a zone of unstable circulation and advantageously the height of the body of coke particles above the chimney should not exceed the diameter of the reaction vessel.

We have found that circulation is maintained within the system without slugging or other interference with uniformity of particle flow and particle-fluid contact at surprisingly low rates of vapor injection for the high L/D ratios involved. We have found that required vapor injection rates are reduced and the circulation is increased by locating the lower end of the internal passageway at the maximum height above the vapor injection point which is possible without causing slugging at a particular vapor injection rate. Thus as the height of the chimney above the point of vapor entry is increased, the rate of coke circulation per given vapor rate increases up to the point of instability.

The principles of operation are illustrated in the following design tests on reactor forms embodying our invention.

In a model of a fluidized coker of 3 $\frac{3}{4}$ " I. D., an internal cylindrical chimney of 1 $\frac{1}{16}$ " I. D. was employed. The coker had a tapered section extending over 4" of height above the vapor injection point. At the vapor injection point, the coker was tapered to 1 $\frac{1}{8}$ " I. D. The circulation was tested by filling the coker with 10-30 mesh coke particles at an air rate of 17 S. C. F. M. in-

4

roduced through the bottom of the reactor. The maximum height for the chimney above the vapor injection point without slugging was 5" as shown below:

	Height	Coke Circulation Rate, lbs./min.	Coke Velocity in Annulus, Ft./min.
10	5"	60.2	22.2 (Verge of slugging).
	4"	46.6	17.2.
	3"	36.0	13.3.
	2"	21.8	8.6.
	1"	8.4	3.1.
	6"	88.3	24.0 (Slugging).

With the chimney at the maximum height of 5", the air rate could be reduced to 13 S. C. F. M. The circulation velocity was 12 ft./min. At an air rate of 16 S. C. F. M., the circulation velocity was 17.1 feet per minute. At an air rate of 19 S. C. F. M., slugging occurred; the chimney was too high. With the chimney at 4", the following data were obtained.

	Air Rate, S. C. F. M.	Circulation Rate, Ft./min.
25	17.0	17.1.
	13.5	10.9.
30	19.0	22.2 (Verge of Slugging).

A plot of data obtained in terms of height in inches against velocity of circulation for different air rates showed that increasing height above the grid increased circulation for a given air rate.

The following data were obtained using a coker having a tapered section extending over 3" of height above the vapor injection point. At the vapor injection point the coker was tapered to 1 $\frac{15}{32}$ " I. D. Slugging first occurred at a chimney height of 13" but recovery to stable operation was effected by reducing the height to 11". The amount of coke in the bed remained constant. The air rate was maintained at 17 S. C. F. M.

	Distance of chimney above vapor injection point, in.	Coke circulation rate, lbs./min.	Coke velocity in annulus, Ft./min.
50	1	0	0
	2	10.9	4.0
	3	14.9	5.5
	4	19.9	7.3
	5	23.4	8.6
55	6	27.1	10.0
	7	32.6	12.0
	8	40.7	15.0
	9	46.4	17.1
	11	50.7	18.7
60	10	50.7	18.7
	12	54.3	20.0
	13	! Slugging	

¹ Recovered stable operation after slugging when lowered back to 11 in.

Using a larger chimney, 2 $\frac{1}{2}$ " O. D. and 2 $\frac{5}{16}$ " I. D., 17.5 S. C. F. M. was established as the minimum air rate. With the chimney height at 7", the circulation rate in the annulus was 11.5 ft./min. At 9", slugging occurred in the annulus, but at 8" slugging stopped and circulation was reestablished at a rate of 15 ft./min. with only occasional minor slugging in the chimney.

The coking reaction is conducted according to our invention by use of a sufficient volume of coke particles of say about 10 to 30-mesh size range to adsorb the net coke make from the oil charged and in a reaction vessel of sufficient volume to accommodate the vapor volumes involved. A high coking temperature is advantageously employed to obtain high capacity in any given sized equipment but a low pressure; e. g. atmospheric or subatmospheric to about 50 p. s. i. g. is employed. Coking temperatures range from about 850° to 1200° F. Ordinarily, the coking temperature within the reaction zone is limited by the heater outlet temperature in preheating the oil charge, usually about 925° to 975° F. for a black oil charge depending upon the particular heater design. Additional heat therefore is usually supplied by superheating the elutriating and circulating vapors injected into

the reaction vessel. However, as described above, operating according to the coke circulating system of our invention readily permits in situ combustion of a portion of the coke make to supply heat within the reaction zone. Additional heat may be supplied using gas burners. The directed circulation path of the coke particles within the body of coke particles in the reaction vessel according to our invention results in progressive flow through oil injection, adsorption, distillation and solid coke formation stages of the reaction without excessive heterogeneous mixing. As a consequence, direct air or oxygen injection to the reaction vessel may be employed in the later stages of coke particle circulation to burn a portion of the coke make without consequent destruction of valuable portions of the oil charge and product. Also flue gases can be separately withdrawn without overloading the product recovery and vapor handling system.

We claim:

1. In the coking of hydrocarbon oils in the presence of a body of coke particles at a coking temperature, the method of maintaining a body of coke particles in a vertically enlarged reaction vessel, circulating coke particles upward through an internal passageway of restricted cross-section within the body of coke particles to an upper level of the body of coke particles by vapor injection below the passageway and downward through an annular zone surrounding the internal passageway, deflecting the downwardly circulating particles through a restricted annular outlet section and inwardly toward the upwardly circulating stream of particles below the internal passageway, passing a preheated charge oil into the body of coke particles below the internal passageway and upwardly through said passageway, selectively withdrawing large coke particles by elutriation with a vaporous elutriation medium from the lower portion of the reaction vessel and withdrawing vapors from the upper portion of the reaction vessel.

2. The method of claim 1 in which the vapor injected for circulation is steam.

3. The method of claim 1 in which a portion of the coke in the downwardly circulating coke particles is burned by air injection at a low point in the annular zone surrounding the internal passageway and in which flue gas is separately removed from the reaction vessel.

4. In apparatus for coking hydrocarbon oils, a vertically enlarged reaction vessel having an inwardly tapered lower section, an elutriator pipe opening into the bottom of the reaction vessel, an open-ended cylindrical chimney

disposed within the reaction vessel with its lower portion cooperating with the tapered section of the reaction vessel to provide an annular outlet section opening into the lower portion of the reaction vessel above the elutriator, means for injecting a circulation vapor at a low point of the tapered section, means for injecting an oil charge stock into the circulation vapor at a point in the lower portion of the reaction vessel below the chimney which then passes upwardly through said chimney, means for injecting a vaporous elutriating medium into the elutriator pipe and means for removing vapors from the upper portion of the reaction vessel.

5. In apparatus for coking hydrocarbon oils, a vertically enlarged reaction vessel having an inwardly tapered lower section, an elutriator pipe opening into the bottom of the reaction vessel, an open-ended cylindrical chimney disposed within the reaction vessel with its lower portion cooperating with the tapered section of the reaction vessel to provide an annular outlet section opening into the lower portion of the reaction vessel above the elutriator, an enlarged annular section in the reaction vessel surrounding the lower portion of the chimney, means for injecting combustion air into the enlarged annular section, means for removing flue gas from the reaction vessel, means for injecting a circulation vapor at a low point of the tapered section, means for injecting an oil charge stock into the circulation vapor at a point in the lower portion of the reaction vessel below the chimney which then passes upwardly through said chimney, means for injecting a vaporous elutriating medium into the elutriator pipe and means for removing vapors from the upper portion of the reaction vessel.
